UNITED STATES PATENT OFFICE.

WILLIAM J. BRADLEY, OF TROY, NEW YORK, ASSIGNOR TO THE RAIL JOINT COMPANY OF NEW YORK, N. Y., A CORPORATION OF NEW YORK.

SECTIONAL SHEARS FOR METAL BARS.

1,108,689.

Specification of Letters Patent. Patented Aug. 25, 1914.

Application filed April 12, 1913. Serial No. 760,623.

To all whom it may concern:

Be it known that I, WILLIAM J. BRADLEY, a citizen of the United States, residing at Troy, in the county of Rensselaer and State 5 of New York, have invented certain new and useful Improvements in Sectional Shears for Metal Bars, of which the following is a specification.

This invention relates to the subject of 10 shearing devices for cutting into predetermined lengths, bars of metal of various cross sectional shapes, and more particularly refers to shears adapted for cutting rolled rail joint bars into joint lengths.

15 To this end, the invention primarily has in view the novel feature of constructing the upper and lower knife members of more than one matching blade section, each of which is separately removable and replaceable 20 and is adaptable to various combinations with other blade sections according to the cross sectional characteristics of the particular bar to be sheared. In this aspect, the invention possesses special utility in its application to shears for shearing rail joint 25 bars of the continuous type, which type of rail joint bar includes an angle splice member adapted to fit the fishing spaces of the rails and an integral continuous base plate 30 constituting a rail seat and support.

According to the usual practice of shearing rail joint bars, the shears employed for that purpose have been provided with single one-piece knife blades for both the upper 35 knife member and for the lower knife member, for each particular section of rail joint, hence, in the event of the breakage of a part of one of these knife blades, an entirely new blade must be substituted therefor, and 40 furthermore it is necessary for the mill to be provided with a complete set of the one-piece knife blades for each particular section of rail joint bar, and since there must also be duplicates of all knife blades in order 45 that breakages may be immediately replaced, it is apparent that a large stock of knives or knife blades must be kept up to supply the demands of the ordinary shears usually employed for shearing rail joint bars to 50 lengths.

It is, therefore, the purpose of the present invention to obviate these conditions incident to the use of the ordinary shears by providing sectional knife members, each section 55 of which is separately and independ-

ently removable and replaceable. This sectional construction of knife possesses special practical advantages from a manufacturing standpoint, in the shearing of rail joint bars particularly of the continuous design. One 60 of these advantages arises from the fact that in the event of breakage of one portion of the knife, that blade section containing the break is the only part to be replaced and it can be done at a comparatively small expense. Another distinct advantage is that 65 where two sections of rail joint bars are alike in some portions, the knife blade section conforming to those portions, can be used on both joint bars, thus involving the 70 feature of each blade section being adaptable to different combinations with other blade sections according to the similarity or dissimilarity of the cross sectional characteristic of different sections of rail joint bars. 75 In connection with this phase of the invention, it is to be observed that the same provides means whereby a less number of knife blades are required to be kept in stock than under the prevailing practice with the ordinary shears, as already alluded to. 80

While the invention is necessarily susceptible of structural modification in various minor particulars without departing from the spirit or scope of the same, a preferred and practical embodiment thereof is shown in the accompanying drawings, in which—

Figures 1 to 4 are similar elevational views illustrative of the sectional shear knife-members adapted for cutting four different types or sections of continuous rail joint bars. Fig. 5 is an elevational view showing a modification of the invention wherein the lower knife member may include a separate renewable tongue piece to facilitate replacing of this part only of the lower knife member or blade. 95

Like reference characters designate corresponding parts in the several figures of the drawings. 100

According to the present invention, the distinctive feature thereof resides in constructing the upper and lower shear knife members in sections, so for illustrative purposes there are shown in the drawings only the sectional shear knife members essential to this invention, which may be mounted in the shearing machine in any suitable manner. In Figs. 1, 3, 4, and 5, the sectional 110

parts 1 and 2 denote filling blocks which may be of any desired form or size to properly compensate for the various sizes of sectional knife members used for the different 5 shapes and sizes of the bars to be sheared.

As shown, the upper knife member consists of the separate blade sections 3 and 4, and the lower knife member consists of the separate blade sections 5 and 6, which are 10 paired in matching contiguous relation so as to perform the same functions of a one-piece knife blade, while at the same time maintaining the sectional or divided characteristics whereby each blade section is 15 capable of being separately removed and replaced without disturbing any other blade section. This enables any one of the several blade sections to be replaced by a similar duplicate section in the event of breakage of any portion thereof, and likewise permits the carrying out of that desirable function wherein a knife blade section that conforms to like parts of two or more different sections of rail joint bars can be used as a 20 part of the shears for shearing the said different sections of rail joint bars.

The matching paired blade sections 3 and 4 which constitute the upper knife member are respectively provided with adjoining 30 and matching cutting edges 7 and 8 which together conform to the configuration and dimensions of one side or face of the metal bar to be cut, while the blade sections 5 and 6 of the lower knife member are likewise respectively provided with adjoining and 35 matching cutting edges 9 and 10 which together conform to the configuration and dimensions of the opposite side or face of the bar.

40 In the exemplification, shown in the drawings, the various bar sections illustrated are different sections of the continuous type of rail joint bar, and accordingly the cutting edges 7-8 of the upper knife member conform to the outer side or face of the bar, while the cutting edges 9-10 of the lower knife member conform to the inner side or face of the bar or vice versa, and it will also be apparent by reference to the various 45 figures of the drawings how any one of the blade sections may be adapted for cutting different sections of the bar which present similar portions for the said section to operate upon.

50 55 The manner of mounting the separate blade sections is non-essential and it will

also be understood that the terms upper and lower are employed in the relative sense only, it being obviously quite immaterial whether the shear members be arranged one over the other for vertical shearing, or one at the side of the other for horizontal shearing, or which of the shear members is the movable one.

By way of illustrating the modification 65 that may be resorted to in carrying out the invention, there is shown in Fig. 5 of the drawings a construction wherein the lower knife member includes as a part of one of the blade sections a separately detachable 70 and renewable tongue piece 5a. This tongue piece is the part which breaks most frequently in shears for cutting rolled rail joint bars into joint lengths, and by making this section of the shear blade comparatively 75 small, and separately detachable and renewable, it can be renewed at less cost and less trouble than by replacing the entire blade section 5, thus materially contributing to the practical advantages of a shear for metal 80 bars having knife members consisting of separately attachable and detachable blade sections.

I claim:

1. A sectional shear for metal bars, each 85 knife member of which consists of a plurality of separately attachable and detachable blade sections having irregular adjoining cutting edges, the combined cutting 90 edges of the two sectional knife members respectively conforming to the outside and inside configurations of the metal bar.

2. A sectional shear for metal bars, each 95 knife member of which consists of a plurality of separately attachable and detachable blade sections, the blade sections of one member having edges arranged to form a re-entrant space, and one of the blade sections of the other knife member having a tongue piece adapted to operate within said space. 100

3. A sectional shear for metal bars including a knife member having cutting edges and a re-entrant space, and another knife member having a separately detachable and renewable tongue piece coöoperating with 105 said space.

In testimony whereof I hereunto affix my signature in the presence of two witnesses:

WILLIAM J. BRADLEY. [L. S.]
